US0D1076674S

(12) **United States Design Patent** (10) **Patent No.:** **US D1,076,674 S**
(45) **Date of Patent:** **** May 27, 2025**

(54) **BOTTLE**

(71) Applicant: **Vollgas Beverage (Shanghai) Co., Ltd.**, Shanghai (CN)

(72) Inventor: **Jianjun Xie**, Shanghai (CN)

(73) Assignee: **Vollgas Beverage (Shanghai) Co., Ltd.**, Shanghai (CN)

(**) Term: **15 Years**

(21) Appl. No.: **29/885,880**

(22) Filed: **Mar. 1, 2023**

(30) **Foreign Application Priority Data**

Sep. 2, 2022 (CN) 202230580634.4

(51) **LOC (15) Cl.** **09-01**

(52) **U.S. Cl.**

USPC **D9/569**; D9/538; D9/516

(58) **Field of Classification Search**

USPC D9/502, 516, 520, 537, 538, 552, 553, D9/554, 556, 569

CPC B65D 79/005; B65D 1/02; B65D 1/0023
